CLAIM

The ornamental design for a display screen or portion thereof with graphical user interface, as shown and described.

DESCRIPTION

FIG. 1 is a front view of a display screen or portion thereof with graphical user interface showing our new design; FIG. 2 is a partially enlarged view of FIG. 1; FIG. 3 is a partially enlarged view of FIG. 1; and, FIG. 4 is a partially enlarged view of FIG. 1.

The outermost broken line depicts a display screen or portion thereof that forms no part of the claimed design. The short-dash long-dash broken line at the periphery of each of FIGS. 2-4 illustrates the boundary of the enlarged portion of FIG. 1, and forms no part of the claimed design. The remaining broken lines in the figures depict portions of the graphical user interface that form no part of the claimed design.
